JAMES HEMPHILL, OF PITTSBURG, PENNSYLVANIA.

Letters Patent No. 78,205, dated May 26, 1868.

IMPROVEMENT IN STEAM-ENGINE SLIDE-VALVES.

The Schedule referred to in these Letters Patent and making part of the same.

TO ALL WHOM IT MAY CONCERN:

Be it known that I, JAMES HEMPHILL, of the city of Pittsburg, in the county of Allegheny, and State of Pennsylvania, have invented a new and useful Improvement in Balance Slide-Valves; and I do hereby declare the following to be a full, clear, and exact description thereof, reference being had to the accompanying drawings, making a part of this specification, which shows a longitudinal vertical section of a steam-chest and slide-valve fitted with my improved devices for balancing the valve.

The nature of my invention consists in the construction of improved devices for balancing sliding-valves, whereby the top of the valve will be almost wholly relieved of the pressure otherwise exerted on it by the steam in the steam-chest, with a consequent saving of friction and wear, and a lessening of the amount of power required to operate the valve.

To enable others skilled in the art to make and use my invention, I will proceed to describe its construction and manner of use.

a a' represent a steam-chest, which may be of any known construction, and having any desirable number or arrangement of steam-ports, *b*, and exhaust-port, *c*, by which the steam-chest *a* is connected with the cylinder. The slide-valve *d*, of any known construction, is operated in the usual way, and for the usual purposes, by a valve-rod, *d'*, passing through a stuffing-box, *e*. On the valve *d* rests a valve-cover, *e*, which is properly steadied in its place by braces attached to it at suitable intervals, and which project against the sides *a* of the chest. A stem, *e'*, extends upward from the valve-cover *e*, through an opening in the top plate *a'* of the steam-chest. This opening is usually of considerable size. A collar, *i*, is made on the stem *e'*, on which rests a relief-plate, *o*, the shape of the plate being such that it will nearly fill the opening left in the top, *a'*, of the steam-chest, its size a little less than the horizontal area of the inside of the valve *d*, and its upper face being even with the upper face of the top, *a'*. On this is fitted a thin metallic packing-disk or diaphragm, *s*, large enough to project entirely over and beyond the opening left in the top, *a'*. Its outer edge is held down fast to the top, *a'*, by a collar, *n*, which is secured to the projecting flange *n'*, or held in place in other convenient way. Over the stem *e'*, I pass another plate, *o'*, usually a little less in area than the lower plate *o*. The plates *o* *o'* and disk *s*, I hold firmly down on to the collar *i*, and at the same time make a tight joint around the stem *e'* by a nut, *f*, screwed on to the upper end of the stem. A cover, *m*, of which the collar *n* may, if desirable, form a part, shuts in the whole, an opening, *g*, however, being left, for the escape of any steam which may leak into the upper cavity of the chest.

The operation of the devices named is, then, as follows: Steam from the boiler is introduced into the steam-chest *a a'*, and the valve *d* is operated by it in the usual way. Without any balancing of the valve *d*, the steam in the steam-chest would press down upon it with a pressure per square inch equal to the pressure indicated by a correct steam-gauge. This would cause enormous loss from friction, wear and tear, and in the amount of power required to operate the valve. But by the use of a relief-plate, *o*, attached to the stem *e'* of the valve-cover *e*, such plate *o* being slightly less than the inside horizontal area of the valve *d*, and secured by packing, as described, I remove or balance the greater part of this downward pressure. The steam exerts a counter-pressure against the plate *o*, and thus acts as a lifting-force, tending to lift the cover *e* off the valve *d*. Then the proportion of the force acting upward against the plate *o*, is to the force acting downward on the valve *d*, as the area of the plate *o* is to the area of the inside of the valve *d*; and the area of the latter should always be slightly in excess of the area of the former, so as to secure a sufficient preponderance in the downward-acting pressure to keep the cover *e* firmly seated on the valve *d*. By the use of these devices I am able to relieve the valve *d* of nearly all the pressure which the steam would otherwise exert, and balance it so perfectly, that but a very small force is required to give to the valve the throw required in operating the engine.

What I claim as my invention, and desire to secure by Letters Patent, is—

The combination of the valve-cover *e*, with its stem *e'*, and the diaphragm *s*, and plates *o* *o'*, arranged substantially as described for the purpose set forth.

In testimony whereof I, the said JAMES HEMPHILL, have hereunto set my hand.

JAS. HEMPHILL.
